UNITED STATES PATENT OFFICE.

CHARLES G. MILLER, OF BRATTLEBOROUGH, OF VERMONT.

IMPROVED CLOTHES-DRIER.

Specification forming part of Letters Patent No. 40,193, dated November 3, 1863.

To all whom it may concern:

Be it known that I, CHARLES G. MILLER, of Brattleborough, in the county of Windham and State of Vermont, have invented a new and Improved Clothes-Bar; and I do hereby declare that the following is a full, clear, and exact description of the same, reference being had to the accompanying drawings, making a part of this specification, in which—

Figure 1 is a front view of my invention; Fig. 2, a side sectional view of the same, taken in the line $\alpha\alpha'$, Fig. 1.

Similar letters of reference indicate corresponding parts in the two figures.

This invention relates to an improved clothes-bar, such as is provided with a series of adjustable arms, and is designed to be attached to the wall of an apartment and hold clothes after being ironed, or to hold the wearing-apparel of the occupant of a sleeping-room.

This invention consists in a novel and simple means employed for preventing the arms from sagging under the weight of the clothes which may be placed upon them, and also consists in a simple means for preventing the clothes from slipping off from the ends of the arms, as hereinafter fully set forth.

To enable those skilled in the art to fully understand and construct my invention, I will proceed to describe it.

A represents a metallic plate, which is secured to the wall of an apartment in any proper way, either permanently or so that it may be readily attached to the wall and detached therefrom. This plate A is provided near its upper end with a horizontal projecting lip, α , and is also provided near its lower end with a similar lip, α' , the latter being smaller than the former.

B is a bolt which passes vertically through these two lips α α' , said bolt being retained in the lips by a head, b, on its upper end, as shown in both figures.

C is a plate which is fitted loosely on the bolt B, so that it may slide freely thereon, the

bolt B below the plate C having a screw-thread cut on it on which a nut, c, works, said nut being between the plate C and the lip α' .

D represents a series of bars or arms through which, near one end, the bolt B passes. These bars or arms are placed one over the other, and they vary in length, the upper one being, the shortest, and gradually increasing in length and projecting farther out from the plate A from the top one downward, the inner ends being in line with each other. The inner ends of the bars or arms are clamped between the upper lip, α , and the plate C by means of the nut c, which may be turned by means of a small wrench. By this arrangement the bars or arms may be firmly held in a horizontal position and effectually prevented from sagging under the weight of the clothes which may be placed upon them, the bars or arms at the same time being allowed to be freely adjusted or turned on the bolt toward or from the wall as may be required. Each bar or arm is provided at its outer end and upper surface with a knob, d, to prevent the clothes from slipping off from the bars or arms. These knobs may be of metal, wood, or other suitable material. The bars or arms are of wood. The nut c may be screwed up at any time to compensate for shrinkage or wear of the bars or arms, so that the latter can always be adjusted and retained in a horizontal position.

I do not claim, broadly, the employment of the swinging bars; but—

Having thus described my invention, what I claim as new, and desire to secure by Letters Patent, is—

The arrangement of the plate C and adjusting-nut, c, with the screw-bolt b, bars D, and lips α α' , all in the manner and for the purpose herein shown and described.

CHARLES G. MILLER.
